RELAY WITH COATED PLUNGER

Chester H. Fluder, Wheeling, Harry L. Myrent, Wilmette, and Matthew R. Heeney, Niles, Ill., assignors to Vapor Corporation, Chicago, Ill., a corporation of Delaware

Filed Aug. 5, 1963, Ser. No. 299,935

4 Claims. (Cl. 200—87)

This invention relates in general to a relay, and more particularly to a relay having a solenoid with a coated plunger, and still more particularly to a relay having a solenoid with a nylon coated plunger.

The relay of the present invention is solenoid actuated and includes many features which enhance its life and decrease its maintenance. Particularly, the moving parts are so constructed and arranged as to reduce their wear and the wear of stationary parts in contact therewith. The plunger of the solenoid in the relay of the present invention, being a part that is subjected to substantial wear, is preferably coated with nylon but may be coated with any other suitable substitute for the purpose of enhancing the life of the solenoid and also reducing the cost of construction.

Heretofore, it was necessary to grind the plunger, specially plate it, and also employ special bearings against which the plunger would engage. Further, a brass shader was necessary on the mating face of the plunger in order to control relay dropout.

It is therefore an object of the present invention to eliminate the above enumerated difficulties and provide a new and improved relay.

A further object of the present invention is to provide a solenoid actuated relay having a plunger coated to enhance the life of the relay and reduce maintenance and construction costs.

A still further object of this invention is to provide a solenoid actuated relay having a nylon coated plunger.

Another object of this invention is to provide a solenoid actuated relay having a nylon coated plunger which eliminates the necessity of grinding and plating of the plunger in order to reduce wear and provide a better bearing surface.

Still another object of this invention is in the provision of a solenoid actuated relay having a nylon coated plunger which eliminates the necessity of providing special bearings and a brass shader on the mating face of the plunger.

A further object of the invention is in the provision of a solenoid actuated relay having a nylon coated plunger, wherein frictional wear is reduced.

Other objects, features and advantages of the invention will be apparent from the following detailed disclosure, taken in conjunction with the accompanying sheet of drawing, wherein like reference numerals refer to like parts, in which:

FIG. 1 is an axial sectional view taken through the relay of the present invention, showing some parts in full view for purposes of clarity; and

FIG. 2 is a perspective view of the solenoid plunger of the present invention.

Referring now to the drawings, the relay of the present invention includes generally a solenoid 10 for operating an upper contact assembly 11 and a lower contact assembly 12.

The solenoid 10 includes a coil 13 having a core or spool 14 of insulating material receiving windings 15. The coil 13 is received between upper and lower bars 16 and 17 of a U-shaped frame 18 that is constructed of magnetic material. A spring washer 19 is inserted between the upper end of the coil and the upper bar 16 in order to hold it against axial movement between the upper and

2

lower bars. A bracket 18a is secured to the frame 18 and serves to mount the relay assembly where desired. The coil 13 is provided with an axial bore 20 that aligns with axial bores 21 and 22 of the upper and lower bars 16 and 17 of the frame 18. An enlarged bore 23 is provided in the upper bar 16 and coacts with the bore 21 to define therebetween a shoulder 24.

An elongated tube 25 of nonmagnetic material is received within the bore 20 of the coil 13, and has secured at its upper end a plug or plunger stop 26 of magnetic material. The plunger stop 26 is provided with an annular flange 27 sized to engage the shoulder 24 in the upper bar 16 and thereby prevent downward movement of the stop and tube through the coil 13. The tube 25 is received over the lower end of the plunger stop and along a diametrically reduced portion, and is secured to the stop by an annular indent 28 engaging in an annular groove on the stop. An axial bore extends through the stop 26 and receives a nylon or suitable plastic sleeve 29, and the lower end of the stop is provided with a conical face 30.

A generally cylindrical plunger 31 of magnetic material is slidably received in the tube 25 and adapted to abut against the conical face 30 when the solenoid 10 is energized. Thus, the upper end of the plunger as designated by the numeral 32 is conical to mate with the conical face 30 of the plunger stop. In order to reduce wear on the plunger 31 and to reduce constructional costs, it is coated or clad with a suitable plastic material such as nylon as indicated by the numeral 33. Thus, the nylon coating 33 engages the tube 25 during operation of the solenoid 10.

An axial bore 34 extends through the plunger 31 to a threaded portion 35, the latter of which receives the threaded end 36 of a post 37 of nonmagnetic material. The post 37 includes a slightly larger cylindrical portion 38 that is slidably received and extends through the nylon insert 29 of the plunger stop 26, and terminates at its upper end with a head 39.

A lower insulating block 40 is secured by a plurality of screws 41 to the upper bar 16 of the frame 18 and includes a bore 42 through which the upper end of the post 37 extends. An upper insulating block 43 is mounted in spaced relation from the lower insulating block 40 and is provided with a plurality of contacts 44, each of which is electrically connected to terminal lugs 45. The contacts 44 are constructed of electrically conductive nonmagnetic material.

Bridge contacts 46 are resiliently mounted on a contact carrier 47 and movable toward and away from the fixed contacts 44. Each bridge contact 46 includes an electrically conductive nonmagnetic bar 48 extending transversely through the upper section 49 of the carrier 47. The opposite ends of the bar 48 are bent downwardly at 50 and contact pads 51 are provided to engage the fixed contacts 44. The carrier 47 also includes a lower section 52 fitting with the upper section 49 and having a recess 53 for receiving a contact support bar 54. A screw 55 extends through the upper and lower sections of the carrier and the support bar and threadedly engages in the head 39 of the post 37 to lock the sections and support bar together and to the post 37 so that the bridge contacts 46 move with the post 37 and the plunger 31 of the solenoid 10.

A spring 56 is bottomed at its upper end in a recess 57 of the upper insulating block 43 and at its lower end in a recess formed in the upper face of the upper carrier section 49. Thus, a constant force is urged to drive the contact carrier and plunger downwardly and such will do so when the solenoid 10 is not energized. Upon energization of the solenoid 10, the force of the spring 56 is overcome to drive the contact carrier 47 up-

wardly so that the bridge contacts 46 engage the fixed contacts 44.

The lower contact assembly 12 includes parallel opposed contact supports 58 and 59 of insulating material mounted on the lower bar 17 of the U-shaped frame 18. Each support carries a plurality of double faced fixed contacts 60 of electrically conductive nonmagnetic material. Lugs 61 are provided for connection to electrical conductors. The contacts 60 and lugs 61 are integral and are molded in the contact supports 58 and 59. A movable contact carrier 62 is arranged between the contact supports 58 and 59. This contact carrier is also constructed of insulating material and includes opposed ears 63 for mounting contact carrier pins 64. Each pin is capable of receiving a bridging contact such as indicated by the numeral 65 that is adapted to engage a pair of spaced fixed contacts 60. The bridging contact 65 is movable along the pin 64 but biased toward the ear 63 by means of a spring 66 that is held on the pin by a retaining clip 67.

The contact carrier 62 is secured to the lower end of the post 37 by means of a threaded bolt 68 having a hex head 69. A tapped bore is provided in the hex head 69 to receive the threaded end 36 of the post and secure the head against the lower end of the plunger 31. A bore 70 is provided in the contact carrier 62 for receiving the threaded bolt 68. Nuts 71 and 72 are provided at opposite sides of the contact carrier 62 and in engagement with the threaded bolt 68 to secure the contact carrier to the bolt and in a desired adjustable position. It should be appreciated that any number of fixed contacts 60 and bridging contacts 62 may be provided to define any number of normally open or normally closed circuits.

It will be understood that modifications and variations may be effected without departing from the scope of the novel concepts of the present invention, but it is understood that this application is to be limited only by the scope of the appended claims.

The invention is hereby claimed as follows:

1. A relay comprising, a coil having a hole extending therethrough, a frame receiving said coil, a tubular member of nonmagnetic material extending through said coil hole and having a plunger stop of magnetically permeable material mounted therein at one end, a plunger of magnetically permeable material slidably received in said tubular member and having a plunger face adapted to abut against said plug when the coil is energized, said plunger having a coating of nylon completely thereover including said plunger face, whereby the coating on said plunger face controls the drop out of the relay and the

coating of the plunger otherwise reduces frictional wear, and contact means operated by said plunger.

2. A relay as defined in claim 1, and a post secured to the plunger and extending from opposite ends, one end of said post extending through said plunger stop, a nylon sleeve bearing in said plunger stop through which the post slides, and said contact means being connected to said post.

3. A relay as defined in claim 2, wherein said contact means includes upper and lower contact assemblies, each contact assembly having spaced contacts, a contact carrier having bridge contacts mounted thereon and adapted to engage the fixed contacts, and means connecting each carrier to said post.

4. A relay as defined in claim 2, wherein said contact means includes upper and lower contact assemblies, said upper contact assembly including a group of permanently fixed contacts arranged in pairs on a support of insulating material, said support extending perpendicular to said post, a group of movable contacts adapted to bridge selected pairs of said fixed contacts, a carrier of insulating material for said movable contacts movable toward and away from said support, means connecting said carrier to said plunger post, a spring bottomed on said support at one end and on said carrier at the other end for urging said carrier and plunger post in one direction during deenergization of said coil, said lower contact assembly including a group of permanently fixed contacts arranged in pairs upon a pair of oppositely disposed supports of insulating material and in a plane perpendicular to said post, a group of movable contacts adapted to bridge selected pairs of said fixed contacts, a carrier of insulating material for said movable contacts positioned between said oppositely disposed supports and movable between said upper and lower positions, and means connecting said lower carrier to said plunger post.
